UNITED STATES PATENT OFFICE.

JOSEPH N. LIGHTHALL, OF CHICAGO, ILLINOIS, ASSIGNOR OF ONE-HALF TO
WILLIAM A. LIGHTHALL, OF SAME PLACE.

LUBRICATOR.

SPECIFICATION forming part of Letters Patent No. 371,080, dated October 4, 1887.

Application filed July 9, 1887. Serial No. 243,866. (No model.)

To all whom it may concern:

Be it known that I, JOSEPH N. LIGHTHALL, a citizen of the United States, residing at Chicago, in the county of Cook and State of Illinois, have invented a certain new and useful Improvement in Lubricators for Hydraulic and other Cylinders, which is fully set forth in the following specification, reference being had to the accompanying drawings, in which—
10 Figure 1 is a side elevation of an apparatus having my improvement applied thereto; Fig. 2, a sectional view taken on the line 1 1 of Fig. 1; Fig. 3, a plan view; Fig. 4, a detail view of a portion of the lubricating device detached; 15 Fig. 5, a face view of one-half of the sprocket-wheel; Fig. 6, a sectional view of the same, taken on the line 2 2 of Fig. 5; and Fig. 7, an elevation of a modified form of lubricating device. Figs. 1, 2, and 3 are on the same scale 20 with respect to each other. The remaining figures are on the same scale with respect to each other, but on an enlarged scale with respect to Figs. 1, 2, and 3.

Like letters refer to like parts in all the figures of the drawings.

My invention relates to lubricators for hydraulic and other cylinders, its object being to provide an automatic lubricating device whereby single-acting open-ended cylinders, 30 either hydraulic or of any other description, shall be automatically supplied with a suitable lubricant for the piston, and which shall be uniformly spread over the interior of the cylinder.

To these ends my invention consists in the combination, with the piston or piston-rod, of a lubricating device attached to and traveling with the same to supply the lubricant to the interior of the cylinder, within which latter it 40 is arranged. This lubricating device may be either fixed in its relation to the part to which it is attached, or it may be revoluble thereon, and in this latter case it may either be revolved by hand or be provided with suitable 45 actuating mechanism for imparting to it a positive revolution.

My invention further consists in a lubricating device of the description above pointed out, which is so constructed in sections as to

adapt it for application to any ordinary form 50 of apparatus without necessitating any alterations in the said apparatus or the removal of any parts of the same.

I will now proceed to describe a construction in which I have practically carried out 55 my invention in one form, and will then particularly point out in the claims those features which I deem to be new and desire to protect by Letters Patent.

In the drawings I have shown my lubricator 60 applied to the cylinder of a hydraulic elevator of what is known as the "Crane" type. In this construction, A represents the cylinder, B the piston, and C the piston-rod, which latter operates the carriage or cross-head D, traveling on the ways d and carrying the drum or pulley wheels E. These parts are constructed and operate in the usual and well-known manner, it being only necessary to state that the cylinder A is a hydraulic cylinder open at one 70 end, as shown. In practice, with the form of lubricator shown, I attach to the open end of the cylinder A a ring or annulus, a, of smaller internal diameter than the cylinder, for the purposes hereinafter pointed out. 75

F represents the lubricator, which in the present instance is shown as mounted on the piston-rod C between two-part or sectional collars C' and C", secured on the said piston-rod. The lubricator consists of a sleeve, f, 80 revoluble upon the piston-rod C and provided with radial arms f', having at their outer ends wipers f", having an outer facing of hemp or other suitable soft and absorbent material to receive and to carry the lubricant and spread 85 the same upon the interior of the cylinder. A gear-wheel, f", is also provided upon the sleeve f, for the purpose of actuating the same, in the manner hereinafter described. The radial arms f' are preferably rectangular in cross-section and are mounted to slide in corresponding boxes, f', provided with coiled springs f", which serve to thrust the wiper-arms radially outward. A removable retaining-plate, f", bolted or otherwise secured to the box f', serves 90 to permit the removal and replacement of the wiper-arms and springs in an obvious manner. In its preferable form the sleeve f is divided 95

into two halves, each half carrying one of the wiper-arms and one-half of the gear f^3 . This construction permits the lubricator to be readily attached to or removed from the piston-rod, the two halves thereof being connected by means of bolts f^7 , passing through lugs f^8 on the two halves of the lubricator, as shown.

G represents a shaft arranged parallel to and preferably above the piston-rod C, and 10 provided at its front end with a pinion, g^3 , which meshes with the gear-wheel f^3 . The front bearing, c , of the shaft G is mounted or formed on the two-part collar C², and its rear bearing, c' , is mounted on a collar, C³, which is 15 also in two parts and surrounds either the piston-rod or, as in the case shown, the hub of the carriage or cross-head D. An intermediate bearing, c^2 , is also provided, which bearing is supported by a two-part collar, C⁴, mounted 20 on the piston C. The collar C³ is also provided with a bearing, h , for a shaft, H, arranged at right angles to the shaft G and provided at its inner end with a bevel-pinion, h' , which meshes with a corresponding bevel-pinion, g' , on the 25 shaft G. At its outer end the shaft H is provided with a sprocket-wheel, H', over which passes a sprocket-chain, H². The sprocket-chain H² is actuated by means of a sprocket-wheel, I, constructed in two parts, one of which 30 is shown in Figs. 5 and 6 of the drawings. This two-part construction is adapted to enable me to place the sprocket-wheel around the shaft E' of the drum or pulley wheels E, and, after being placed in position, the two 35 halves of the sprocket-wheel are bolted or otherwise secured to the spokes or hub of the said drum or pulley wheels by means of bolts passing through the apertures i, formed therein for this purpose.

40 The apparatus thus constructed operates in the following manner: A proper quantity of the lubricant—say, for instance, a quart of lubricating-oil—is poured into the cylinder A, at the bottom of which it is retained between 45 the piston B and the ring a. As the piston reciprocates, the drum or pulley wheels E rotate, and the rotary motion is imparted, through the medium of the sprocket-wheel I, chain H², shafts H and G, with their gearing, and the 50 gears g^3 and f^3 , to the lubricator F, which is thus caused to rotate slowly around the piston-rod C. The lubricator also partakes of the reciprocating motion of the piston-rod, and this motion, in combination with its movement of 55 rotation, serves to spread or distribute the lubricant evenly over the entire surface of the cylinder, the wipers collecting the oil which lies in the bottom of the cylinder at each revolution, and during the remainder of their travel 60 spreading the same in the manner just referred to.

It will be observed that all the parts of the lubricator and its operating mechanism are so constructed in sections that they are capable 65 of application to the main apparatus without in any way changing or altering this latter and

without necessitating the disconnecting or removal of any of the parts thereof. Such a construction obviously enables me to apply the lubricator to an apparatus which is already 70 set up and in operating position.

Although in the preferred form which I have shown and described the lubricator is revolvable and is provided with means for positively rotating it, I do not limit myself to such a construction, as a lubricator fixed upon the piston or piston-rod may be employed. For instance, in Fig. 7 of the drawings I have shown a two-part wheel, J, the two halves being connected by bolts j, and the said wheel being provided with a groove-periphery, j', to receive the packing J', of hemp or other suitable material. In the bottom of the groove j' beneath the packing J' is arranged a strip of metal, J², fitting loosely within the groove and adjustable by means of screws j², to force the packing J' outward as it wears away. A wheel of this description may be fixed upon the piston-rod C, or may be mounted thereon so as to revolve freely, in which latter case the wheel will 90 be turned by hand at suitable intervals, so as to bring a fresh surface into contact with the cylinder. Any other suitable form of lubricating device may be employed, and I do not limit my invention to the particular forms 95 shown and described.

Various modifications of the details of construction may be made without departing from the principle of my invention. For instance, although I have shown my invention 100 as applied to a horizontal hydraulic cylinder, it is obviously applicable to a vertical cylinder, and also to cylinders other than hydraulic—such, for instance, as the cylinders of hot-air engines and the like. I therefore do not wish 105 to be understood as limiting myself strictly to the precise details hereinbefore described, and shown in the drawings.

Having thus described my invention, what I claim as new, and desire to secure by Letters 110 Patent, is—

1. The combination, with the open-ended cylinder and its piston and piston-rod, of the lubricator mounted on the piston-rod and revolvable thereon, and the pulley-wheels E, connected to the said lubricator to actuate the same, substantially as and for the purposes specified.

2. The combination, with the cylinder A, piston B, and piston-rod C, having cross-head D, with drum or pulley wheels E, of the lubricating device F, mounted to revolve on the piston-rod and having gear f^3 , the shaft G, having pinion g^3 and bevel-pinion g' , the shaft H, having bevel-pinion h' and sprocket-wheel H', the sprocket-wheel I, and sprocket-chain H², substantially as and for the purposes specified.

3. The combination, with the horizontal cylinder A, having piston B, piston-rod C, and the revolvable lubricator mounted on said piston-rod, of the retaining ring or annulus a,

secured to the open end of the cylinder and projecting inward a slight distance only, substantially as and for the purposes specified.

4. The combination, with the cylinder and 5 its piston and piston-rod, of the lubricator mounted to revolve on the piston-rod and constructed in two separable halves, the collars supporting the bearings of the actuating gearing, also constructed in two separable halves, 10 and the two-partsprocket-wheel, substantially as and for the purposes specified.

5. The combination, with the open-ended cylinder and its piston and piston-rod, of the

lubricator mounted on the piston-rod and provided with a facing of hemp or other absorbent 15 material held against the inner surface of the cylinder by an elastic or yielding pressure, substantially as and for the purposes specified.

6. The combination, with the sleeve *f*, having boxes *f*⁴, with coiled springs *f*⁵, of the 20 wiper-arms *f*⁶, arranged in said boxes, substantially as and for the purposes specified.

JOSEPH N. LIGHTHALL.
